(57) **CLAIM**

The ornamental design for a luminaire, as shown and
described.

DESCRIPTION

FIG. 1 is a perspective view of a luminaire showing my
design;

FIG. 2 is a front elevational view thereof;

FIG. 3 is a right side elevational view thereof;

FIG. 4 is a bottom plan view thereof; and,

FIG. 5 is a top plan view thereof.

The rear elevational view is a mirror image of front eleva-
tional view and, therefore, has been omitted. The left side
elevational view is a mirror image of the right side eleva-
tional view and, therefore, has also been omitted.
